REFRIGERATING UNIT

Henry E. Elrod, Houston, Tex.

Original application March 14, 1930, Serial No. 435,889. Divided and this application September 18, 1931, Serial No. 563,618

4 Claims. (Cl. 62—115)

The present invention relates to a condenser unit comprising, essentially, a motor, a compressor, a coil, a fan, and a heat-radiating enclosing hood for the coil, motor, and fan. The unit is so designed that although it may be built into a refrigerating box at the factory, it may be equally well applied to an ordinary ice box to convert the same into a mechanical refrigerator. The features of the general assembly are disclosed and claimed in the instant application, which is a division of application Serial Number 435,889, filed March 14, 1930.

According to the embodiment of the invention to be described hereinafter, the motor is mounted within the coil in coaxial relation thereto and the fan and compressor, which latter is preferably of the rotary type, are coaxial with the motor. The elements are all supported by a base plate, the motor and fan being disposed at one side of the plate and the compressor at the other side in a housing preferably integral with the plate. A hood of heat-radiating material surrounds the coil in proximity thereto and has air openings through which air is drawn and expelled by the fan, the air in its passages through the hood passing along the coil to cool the same. The hood radiates outwardly heat transmitted thereto from the coil and also serves to protect the mechanism enclosed by it. It offers a further advantage, as over an exposed coil, in that dust and dirt do not readily gather on it and it may be easily cleaned.

My invention is best illustrated by reference to the accompanying drawing which is an axial section through the preferred embodiment of my unit, parts being shown in elevation.

In the drawing, reference numeral 10 designates a circular horizontal base plate having centrally thereof a cylindrical, depending integral skirt 11. Plate 10 is provided with a central circular aperture 12 surrounded by an upstanding collar 13. A condensing coil 14 rests on the upper margins of plate 10 with its axis perpendicular to the plate. The coil outlet 15 to an expansion valve, not shown, passed downwardly through a peripheral recess 16 of plate 10.

An electric motor 17 is mounted on a tripod 18, whose legs are secured to plate 10, coaxially with coil 14 and with its armature shaft 18 passing downwardly through and centrally of aperture 12. A substantially bell-shaped hood 19 of heat radiating material surrounds the coil and motor with its lower margins resting against the

periphery of plate 10, and, if desired, removably secured thereto.

Near its lower edge hood 19 is provided with a number of air holes 20, while at its top it is provided with a central air escape aperture 21 through which the upper armature shaft bearing of the motor projects for convenient oiling through duct 22.

Mounted on armature shaft 18 beneath the motor is a fan 23, here shown as comprising four blades, adapted, upon armature rotation, to draw air into the hood through holes 20, circulate it upwardly along the coil, and expel it from the hood through aperture 21.

A conduit for the electrical conductors to the motor and to a thermoswitch (not shown) is secured to the motor casing and extends downwardly through an aperture in plate 10. The conductors may be led to the conduit 24 through a hole 20 of hood 19 and a T coupling 25 interposed in the conduit.

To install the condenser unit in an ice refrigerator, it will be evident that it will only be necessary to cut holes in the T of the box above the ice compartment to receive pipe 15, conduit 24, and skirt 11, plate 10 then being adapted to rest directly on the top T of the box.

The inlet end of coil 14, through a connection 26, is in communication with the interior of skirt 11.

Referring now to the drawing, skirt 11 is closed at its lower end by means of a circular plate 27 having a flat-topped, raised portion 28 extending upwardly within the skirt. Portion 28 is centrally bored to receive the lower end of shaft 18. Fixed to shaft 18 immediately above portion 28, and having a lower flat face resting upon the face of the latter, is a cylindrical block 29 fixed in position by means of a set screw 30. Block 29 is provided with a number of bores parallel to shaft 18 and with their axes defining a circle concentric with the shaft. In these bores are slideable pistons 31 whose upper ends are guided in a flange 32 integral with block 29. A cam ring 34 is secured by means of a flange 35 to the lower margins of aperture 12 and has an axially projecting cam face 36 opposed to and in the circle of pistons 31.

Intermediate block 29 and flange 32 pistons 31 are provided with abutments 38. Interposed between abutments 38 and block 29 are compression springs 39 which yieldingly urge the upper chamfered extremities of pistons 31 against cam face 36. Upon rotation of block 29 pistons 31 will be reciprocated by the cam and springs.

These pistons operate upon a fluid introduced into the interior of skirt 11 to compress the same.

Having described my invention, I claim:

1. A condenser unit comprising a horizontal base plate adapted to rest upon the top of a cabinet, a coil mounted on said plate with the axis thereof perpendicular to said plate, a motor mounted on said plate in coaxial relation within the coil, a rotary compressor supported by the plate at its side opposite the coil and extending below the top of the cabinet in coaxial relation to the motor, and a drive shaft connecting the motor and compressor.
2. A condenser unit comprising a horizontal base plate adapted to rest upon the top of a cabinet, a coil mounted on said plate with the axis thereof perpendicular to said plate, a motor mounted on said plate in coaxial relation within the coil, a rotary compressor supported by the plate at its side opposite the coil and extending below the top of the cabinet in coaxial relation to the motor, a drive shaft connecting the motor and compressor, and a fan mounted on the shaft for circulating air upwardly along the coil.
3. A condenser unit comprising a horizontal base plate, a coil mounted above the plate with

its axis perpendicular thereto, a motor mounted on a vertical axis within the coil, a rotary compressor mounted below the plate in coaxial relation with the motor, a drive shaft connecting the motor and compressor, a housing for the compressor depending from the plate, a fan on the drive shaft for circulating air upwardly along the coil, and a substantially bell-shaped hood of heat radiating material surrounding the coil in proximity thereto, said hood having top and bottom air openings.

4. A condenser unit comprising a horizontal base plate adapted to rest upon the top of a cabinet, a coil mounted above the plate with its axis perpendicular thereto, a motor mounted on a vertical axis within the coil, a compressor mounted below said plate in coaxial relation with said motor, a drive shaft connecting the motor and compressor, a housing for said compressor depending from said plate below the top of the cabinet, and a substantially bell-shaped hood of heat-radiating material surrounding the coil in proximity thereto, said hood having top and bottom air openings.
